UNITED STATES PATENT OFFICE.

ALEXANDER JOHNSTON, OF EDINBURGH, SCOTLAND.

DESIGN FOR A TIRE.

45,092.

Specification for Design.

Patented Dec. 30, 1913.

Application filed August 1, 1913. Serial No. 782,528. Term of patent 14 years.

To all whom it may concern:

Be it known that I, ALEXANDER JOHNSTON, a subject of the King of the United Kingdom of Great Britain and Ireland, residing at 3 Strathearn road, Edinburgh, Scotland, have invented a new, original, and ornamental Design for Tires, of which the following is a specification, reference being had to the accompanying drawings, forming part thereof.

Figure 1 of the accompanying drawings is a plan view illustrating a section or portion of a tire. Fig. 2 is a perspective view of a portion of a complete tire.

The tire tread consists of a raised central strap or ridge *a* extending continuously

around the tire and having extensions forming crosses *b* and diamonds or squares *c*, arranged alternately with the crosses and at uniform distances apart.

Claim:

The ornamental design for a tire tread having a central strap extending continuously around the tire and having extensions thereon forming cross pieces and diamond or square parts arranged alternately, substantially as described and shown.

ALEXANDER JOHNSTON.
